US0D1097053S

(12) **United States Design Patent** (10) **Patent No.:** **US D1,097,053 S**
(45) **Date of Patent:** **** Oct. 7, 2025**

(54) **ARTIFICIAL BAIT**

(71) Applicant: **Shandong Handing International Trade Co., Ltd**, Weihai (CN)

(72) Inventor: **Chao Liu**, Weihai (CN)

(73) Assignee: **SHANDONG HANDING INTERNATIONAL TRADE CO., LTD**, Weihai (CN)

(**) Term: **15 Years**

(21) Appl. No.: **29/942,139**

(22) Filed: **May 14, 2024**

(30) **Foreign Application Priority Data**

Apr. 9, 2024 (CN) 202430192726.4

(51) **LOC (15) Cl.** **22-05**

(52) **U.S. Cl.**

USPC **D22/133**

(58) **Field of Classification Search**

USPC D22/125, 126, 130, 131, 132, 133;
43/42, 42.1, 42.21

CPC A01K 85/00; A01K 85/005; A01K 85/021;
A01K 85/14

See application file for complete search history.
